[57] CLAIM

The ornamental design for a putter head for a golf club, as shown.

DESCRIPTION

FIG. 1 is a perspective view of the putter head for a golf club showing my new design;

FIG. 2 is a front elevational view of the putter head;

FIG. 3 is a side elevational view of the putter head, which side is distal from the golf club shaft;

FIG. 4 is a bottom view of the putter head;

FIG. 5 is a top view of the putter head;

FIG. 6 is a side view of the putter head of the side proximal to the club shaft; and,

FIG. 7 is a rear view of the putter head.

FIG. 1

FIG. 2

FIG. 3

FIG. 4
